UNITED STATES PATENT OFFICE.

JESSE M. PORTER, OF CUYAHOGA FALLS, OHIO.

SAFETY-DOOR FOR ELEVATORS.

No. 828,965.

Specification of Letters Patent.

Patented June 19, 1906.

Application filed July 15, 1905. Serial No. 269,805.

To all whom it may concern:

Be it known that I, JESSE M. PORTER, a citizen of the United States, residing at Cuyahoga Falls, in the county of Summit and 5 State of Ohio, have invented new and useful Improvements in Safety-Doors for Elevators, of which the following is a specification.

This invention relates to safety-doors for elevator-shafts, designed especially for preventing the spread of fire through the latter, and has for its objects to produce a comparatively simple inexpensive device of this character which may be readily installed for use, one in which the doors will remain normally closed and effectually prevent communication between the floors of the building through the elevator-shaft, and one wherein the doors will be automatically opened by the elevator in traveling up or down the 20 shaft and will after passage of the cage return automatically to closed position.

Further objects of the invention are to provide a device of this class in which the doors will travel smoothly and evenly, one in the 25 operation of which undue shocks will be obviated, and one wherein the doors will be positively maintained in open position during passage of the elevator-cage therebetween.

With these and other objects in view the invention comprises the novel features of construction and combination of parts more fully hereinafter described.

In the accompanying drawings, Figure 1 35 is a vertical longitudinal section centrally through a portion of an elevator-shaft equipped with mechanism embodying my invention. Fig. 2 is a horizontal sectional plan showing the safety-doors open and the 40 elevator-car passing therebetween. Fig. 3 is a side elevation of the elevator-car, showing the parts of the mechanism carried thereby. Fig. 4 is an enlarged detail view, partly in 45 vertical longitudinal section, of one of the guides and its attendant door-operating devices. Fig. 5 is an enlarged detail view, partly in section, of a portion of the guide, showing the carriage arranged for travel therein. Fig. 6 is a transverse section taken 50 on the line 6-6 of Fig. 5. Fig. 7 is a detail sectional view of a portion of one of the doors and door-guides. Fig. 8 is a top plan view of the parts illustrated in Fig. 7. Fig. 9 is a detail section showing parts of the pair of 55 doors in closed position. Fig. 10 is a top plan view of the parts shown in Fig. 9.

Referring to the drawings, 1 designates an elevator-car, 2 its shaft, and 3 the floor of the building through which the latter passes, these parts, except as hereinafter explained, 60 being all of the usual construction and adapted to perform their ordinary functions.

Disposed respectively on opposite sides of the shaft and adapted for coöperation to close the latter is a pair of substantially horizontal 65 doors 4, arranged for sliding movement in and sustained by guides 5, preferably composed of sections of channel-iron having at suitable spaced intervals perforated bracket-ears 6 for attachment to the framework of 70 the floor 3 and each presenting a pair of spaced parallel portions or flanges 7, designed to receive the adjacent edge of one of the doors between them, the flanges 7 being channeled to form runways 8, in which are arranged 75 antifriction-balls 9, bearing in shallow V-shaped grooves 10, formed in the door, while the guides 5 are slightly inclined from the horizontal downward toward the shaft 2 for insuring automatic movement of the doors 80 to closed position. The doors 4, which are similar in construction, each includes a marginal frame 11, having attached thereto by means of screws or other fastening devices 12 a pair of steel or other sheet-metal side plates 85 13, spaced to receive between them a filling 14, of asbestos or other fireproof material, there being journaled at appropriate points in the forward edges of the doors flanged guide-rollers 15 for a purpose which will presently appear, said edges of the doors being also provided with recesses 16, which 90 conjointly form an opening for the passage of the hoisting-cable when the doors are closed, while one of the doors has its forward edge 95 recessed at 17 to form an opening between the doors for the passage of the feed-cable of electric elevators.

Journaled in suitable bearings at the outer or rear ends of the guides 5 are horizontal 100 pulleys 18, having arranged for travel thereon flexible traction elements or cables 19, attached at 20 to the rear edges of the doors and having their free ends engaged with blocks or carriers 21, arranged for travel in 105 vertical guides 22, fixed at appropriate points within the shaft 2, the carriers, which are equipped with antifriction-rollers 23, being provided with contact portions or fingers 24, designed to project outward through and 110 travel in longitudinal slots 25, provided in the outer front walls of the guides 22, while

attached to and carried by the car 1 at the corners thereof are upwardly and downwardly projecting engaging elements or arms 26, provided at their outer terminals with engaging portions or fingers 27, designed to contact with the projecting portions 24 of the carriers for exerting traction upon the elements 19 to open the doors. Applied to the active faces of the portions or fingers 27 are rubber or other buffers 28, which obviate undue noise and shock incident to the fingers coming in contact with the portions 24. The elements 19 pass into the guides 22 through suitable openings 29, formed in the rear walls of the latter, there being journaled in line with each of the openings a pair of vertically-disposed guide-pulleys 30 and at the ends of the opening antifriction-rollers 31, over which latter and the pulleys 30 the elements 19 are adapted to travel during the operation of the device, while the carrier-blocks 21 are connected by transverse pins 32, designed to engage terminal loops or eyes 33 on the ends of the cables, thus adapting the carriers to move freely either upward or downward within the guides, which have rearwardly-curved terminal portions 33' to receive the carriers and retract the contact portions 24 out of the path of movement of the engaging portions 27 for a purpose which will presently appear.

Fixed upon the side faces of the car 1 at appropriate points are rigid vertical guide members or rails 34, designed to register and travel in contact with the flanged rollers 15, while the car is passing between the doors, said guides being extended slightly above and below the car, whereby the latter will have wholly passed the doors prior to release of the same for movement to closed position.

Disposed between the meeting edges of the doors are rubber or other yieldable buffers 35, preferably of semispherical form and adapted to enter corresponding sockets or recesses 36 to insure complete closing of the doors, these buffers being intended for preventing undue noise and shocks when the edges of the doors meet in closing.

In practice the doors normally stand in closed position, as illustrated in Fig. 1, under which conditions the elements 19 will be withdrawn from the guides 22 and the carriers 21 will stand in a position adjacent the longitudinal centers of the latter in line with the openings 29 and pulleys 30. As the car 1 moves upward or downward in the shaft 2 the engaging portions 27 of arms 26 will engage the contact portions 24 of the carriers, thereby moving the latter upward or downward in their guides 22 and exerting traction upon the elements 19 for opening the doors to permit passage of the car therebetween, it being understood that as soon as the doors are completely opened the rails 34 will engage the rollers 15 and the carriers 21 will 65 pass into the curved portions 33' of the guides

for moving the contact-fingers 24 out of the path of the fingers 27, whereby as soon as the car has traveled beyond the doors the latter will, owing to the downward inclination of the guides 5, move automatically by gravity to normally closed position. It is apparent that under this arrangement the doors will be automatically opened by the carriage during either its upward or downward travel and that the doors will serve normally to effectively close the elevator-shaft and prevent spreading of fire through the latter from one floor to another of a building.

Having thus described my invention, what I claim is—

1. In a device of the class described and in combination with an elevator-car and its shaft, a horizontally-movable door adapted to move automatically to position for closing the latter, a guide sustained within the shaft, a contact member arranged for travel in the guide, and a traction element connected with said member and engaged with the door, said contact member being operable by the car for exerting traction on the element to open the door.

2. In a device of the class described and in combination with an elevator-car and its shaft, of a horizontally-movable door adapted to move automatically to position for closing the latter, a traction element connected with the door, a vertical guide sustained within the shaft, a contact member connected with the element and movable vertically in the guide, and means carried by the car for engaging the contact member to exert traction upon the element to open the door.

3. In a device of the class described and in combination with an elevator-car and its shaft, of a horizontally-movable door for closing the latter, a traction element connected with the door, a vertical guide sustained within the shaft, and a contact member arranged for movement vertically in the guide and connected with the element, said contact member being operable by the car for exerting traction on the element for opening the door.

4. In a device of the class described and in combination with an elevator-car and its shaft, of a horizontally-movable door for closing the latter, a traction element connected with the door, a vertical guide sustained in the shaft and having a curved portion, and a contact member connected with the element and arranged for vertical movement in the guide, said member being operable by the car for exerting traction on the element to open the door and being movable through the curved portion of the guide out of the path of movement of the car.

5. In a device of the class described and in combination with an elevator-car and its shaft, of a horizontally-movable door for closing the latter, a traction element con-

nected with the door, a vertical guide sustained in the shaft, a contact member mov-
ably sustained by the guide for vertical
movement and connected with the element,
5 and an arm carried by the car and having an
engaging portion adapted for engaging and
operating the contact member to exert trac-
tion on the element for opening the door.

6. In a device of the class described and in
10 combination with an elevator-car and its
shaft, of guides extended transversely of the
shaft and arranged at an inclination rela-
tively to the horizontal, a door slidably dis-
posed in the guides and adapted to move au-
15 tomatically by gravity to closed position,
vertical guides sustained within the shaft,

carriages arranged for travel respectively in
the vertical guides and having projecting
contact portions, traction elements connect-
ed with the outer end of the door and with 20
the carriages, arms fixed to and projecting
above and below the car, said arms having
terminal contact members adapted to act
upon the projecting portions of the carriages
for operating the latter to exert traction on 25
the elements and open the door.

In testimony whereof I affix my signature
in presence of two witnesses.
